UNITED STATES PATENT OFFICE

2,638,612

SYRINGE CLEANER

Walton A. Johnson, Elberton, Ga.

Application October 24, 1949, Serial No. 123,238

1 Claim. (Cl. 15—21)

1

My present invention relates to the general class of portable, motor-operated appliances of the liquid treatment type for brushing and cleansing the interior surfaces of hollow or tubular work, and more specifically to a syringe cleanser, or electrically operated brushing appliance, which, while well adapted for various purposes and uses is especially designed for professional use by nurses and others in hospitals, laboratories, and other institutions for maintaining hollow instruments in sanitary condition.

In actual use in a hospital the removable parts of a typical hypodermic syringe or injector are separated, the needle and plunger are cared for, and the hollow cylinder of the syringe is dipped into a liquid cleanser, the liquid content is sealed or closed by a finger or thumb against the outer end of the cylinder, and then the cylinder is manually slipped up and over a rotating brush. The loaded cylinder is thus held for a period of time until the internal surface of the cylinder has been cleansed of any oily film, or other residue; the work is then manually withdrawn from the rotating brush, any remaining liquid is emptied from the washed cylinder, and the cylinder is rinsed in a bath of hot water to insure sanitary working condition for subsequent use.

The primary purpose of the invention is the production of a power operated and manually controlled brushing appliance to which the work is manually applied, and which consists of a minimum number of parts that may with facility be manufactured at comparatively low cost of production, and the parts may be assembled with convenience to assure safety for the operator and a quick and thorough cleansing of the hollow ware. To this end the invention consists in certain novel features of construction and combinations and arrangements of parts as will hereininafter be described and more particularly set forth in the appended claim.

In the accompanying drawings I have illustrated a dual brush appliance constructed and arranged in accord with one mode I have devised for the practical application of the principles of the invention, but it will be understood that changes and alterations are contemplated and may be made in these structures, within the scope of my claim, without departing from the principles of the invention.

Figure 1 is a view in front elevation of the portable appliance in which the invention is embodied.

Figure 2 is a vertical sectional view of the structure of Fig. 1.

2

Figure 3 is an enlarged, detail elevation, with parts in section of one of the dual brushes and its holder; and

Figure 4 is a view of a typical glass hypodermic syringe as an example of the work to be cleansed.

The operating parts of the appliance are enclosed within an open front and preferably open top housing or cabinet that may rest upon a table, or be suspended from a support, and adjacent to a lavatory; and in position where it is readily accessible for use. The housing, which may be fashioned of suitable material and in required size, has a rear upright or perpendicular wall 4, and two laterally spaced side walls 2, 2, that provide guards against splashes from the liquid cleansers as well as safety shields for the brushes, and a horizontal bottom 3. At the open front of the housing its bottom terminates in a front upright retaining flange or lip 4 to prevent displacement of two liquid containers, as an alcohol tray 5 having a sponge 6 deposited therein, and a liquid soap tray 7; and these removable trays with their contents form a bottom for the operating space within the housing.

In order to graphically illustrate the utility of the brushing appliance a glass syringe is shown in Fig. 4, from which the separated needle N is temporarily stowed in the sponge 6, and when the plunger P is removed from the tube or hollow cylinder C, the cylinder is initially dipped by hand into the contents of the alcohol tray in preparation for a brushing operation. After this first operation, the cylinder may be dipped into the liquid-soap tray to make ready for the second brushing operation.

One or more brushes of standard type and varying sizes are mounted within the housing by means of a single bracket as 10 that is fastened by screws or screw bolts 11 and nuts 12 against the inner face of the rear upright wall in the upper part of the housing. The rotary brushes 3 and 9 are operated with power from a typical electric motor 13 that is mounted on the bracket with screws or bolts, and the motor is equipped with a manual switch 14, and connections 15 for plugging into a customary electrical outlet box as a source of supply.

The electric motor is rigidly mounted with its shaft 16 disposed in a plane oblique to the perpendicular rear upright wall of the housing, and the brush 3, which is axially aligned with the shaft, thus declines forwardly toward the open front of the housing, with its free end terminating at a convenient elevation above the bottom trays, 5 and 7. By this combination and ar-

angement of parts within the housing ample free space is provided for the operator in order that the cylinder may be dipped into one of the trays, upended, and then slipped over a brush, as 8, and with equal facility the cylinder may be manipulated for cleansing, and then withdrawn from the brush.

For the brush 8 a tubular holder 17 is attached by set screw 18 to the motor shaft 16, and the lower end of the holder is equipped with a chuck including a knurled nut 19 having a tapered end and threaded on the holder, and the nut clamps a resilient head 21, slotted at 22, on the inserted stem 23 of the brush, a guide stem 24 of the head being employed for centering the clamp head. The rigidly mounted motor provides a stable support for the rotary shaft and the axially alined holder and brush and the rotary motion and power from the shaft are transmitted directly to the holder and its brush.

The larger brush 9, arranged in parallelism with the brush 8, and spaced therefrom, is preferably driven at a lower speed than the smaller brush, by means of a belt drive from the motor shaft through drive pulley 25, which is fixed in adjusted position on the shaft by set screw 26, through belt 27 and a larger pulley 28 fixed by set screw 29 on a driven shaft 30.

The rotary driven shaft 30 is mounted in a suitable ball bearing 31 that is disposed in an oblique plane and attached by screws as 32 to the bracket, to position the driven shaft and brush 9 in parallelism with the motor shaft and brush 8.

A second tubular brush holder 33 is fixed by set screw 34 on the driven shaft, and the brush 9 is clamped to the holder by a chuck including the clamp nut 35 and resilient slotted head 36

into which the stem 37 of the brush is clamped and rigidly held.

The brushes, which are quickly detachable, may be interchanged with other types of brushes in adapting them to different kinds of work, and they may readily be replaced when worn; and the trays may be supplied with appropriate treating liquids required for use under variable conditions.

Having thus fully described my invention, what I claim as new and desire to secure by Letters Patent is:

In a syringe cleaner including an open-front housing, an electric motor mounted therein, and a motor shaft, the combination with a tubular holder detachably mounted on the shaft, and a rotary brush having a stem axially alined with the holder, of a resilient clamp head on the stem, an elongated and tubular lock-nut threaded on the holder, and said lock-nut having a free end embracing the resilient head for clamping said head on the brush-stem.

WALTON A. JOHNSON.
